CARBURIZING MECHANISM

Daniel V. Scullen, Cohoes, N. Y., assignor to General Motors Corporation, Detroit, Mich., a corporation of Delaware

Application January 12, 1939, Serial No. 250,602

4 Claims. (Cl. 266—5)

This invention relates to carburizing mechanisms for iron and steel articles, and more particularly to a furnace for case hardening small articles in bulk.

An object is to provide an improved carburizing mechanism which facilitates an even distribution of the carburizing gases and produces a fast, uniform carburizing operation simultaneously on a multiplicity of work pieces.

Another object is to provide a retort having a plurality of carburizing chambers so constructed as to uniformly distribute the work, and which produces even heating of the work and uniformly presents the work surfaces to the carburizing gas.

A further object resides in the provision of a reinforced multi-chambered retort so constructed that it does not tend to distort or crack when subjected to extreme temperature changes, and which reduces the tendency of injury to the work during a carburizing operation.

To these ends and also to improve generally upon devices of the character indicated, the invention consists in the various matters herein-after described and claimed.

In the accompanying drawings:

Figure 1 is a longitudinal section through my carburizing mechanism taken substantially along the line 1—1' of Figure 3;

Figure 2 is an enlarged fragmentary view showing the coupling in the infeed duct;

Figure 3 is a view of the effluent end of my carburizing mechanism; and

Figure 4 is a fragmentary cross section taken substantially along the line 4—4' of Figure 1.

Generally stated, my carburizing mechanism is herein shown in the form of a furnace 10 supported by the transversely extending co-axial pivots 11 received within the frames 12 at each side of the furnace so that the furnace may be longitudinally tilted to facilitate loading and unloading of the work. My furnace contains the substantially cylindrical rotatable retort 13 provided with an intermediate work-holding portion 14 which is divided into a plurality of work-carburizing chambers 15, each of which may receive a large number of work pieces loosely mounted in bulk for a carburizing operation. I have found that dividing the work-holding portion 14 into a plurality of chambers greatly increases the efficient and reliable operative capacity of the retort, since the carburizing gas may be more uniformly distributed through each of these chambers 15, and the rotation of the retort evenly and loosely distributes the work in each cham-

ber, which results in a better and more uniform heating of the work without injury to the work while the carburizing gas contacts all of the work surfaces to simultaneously produce the same even depth of case-hardening on each work piece.

In the illustrated embodiment, the tubular work holding portion 14, of reduced diameter, is divided into the four sector-shaped carburizing chambers 15 provided with the common transverse end wall 18 and separated by the substantially radial walls 19 which are joined to the end wall 18 and extend through the length of the work holding portion 14 between the outer retort wall and a central hollow core 21 that axially projects from the end wall 18 for the entire length of the carburizing chambers. The outer end of the core 21 is closed at 22, and the tubular retort ends 23 and 24, which respectively and freely extend through and substantially close the cylindrical apertures 25 and 26 in the furnace ends, are rotatably and respectively supported by the sets of rollers 28 and 29 mounted on the shafts 31 and 32 projecting from the ends of the furnace 10. The rollers 29 fit within the peripheral grooved track 33 in the head 34 secured as by the screws 35 to the retort end 24, and a suitably driven sprocket 36 is secured to the head 34 so that the retort may be rotated within the furnace. The rollers 28 at the retort end 23 engage the cylindrical outer retort wall in spaced relation to the annular end flange 37 so that the retort may longitudinally slide as well as rotate on these rollers and expansion and contraction of the retort will not be restricted under influence of temperature changes.

A supply duct 40, which carries a suitable carburizing gas, is universally and rotatably connected through a coupling generally indicated at 41 to the feed pipe 42 that axially extends through the sprocket 36 and the retort end 24. The inner end of the pipe 42 is threaded within the bore that extends through the boss 43 on the dome shaped cap 44. The cap, which has a stepped rim 45 fitted against the annular seat 46 adjacent the outer face of the wall 18, cooperates with the wall 18 to provide the gas expansion chamber 48 that receives the carburizing gas from the infeed pipe 42 and uniformly distributes this carburizing gas into the carburizing chambers 15 through the ports 50 in the wall 18. Each of these ports 50 is preferably substantially centrally located with respect to its chamber 15 so that the gas will be uniformly distributed into carburizing chambers and will evenly contact the work surfaces.

The coupling 41 which may be of various forms, is here shown as having a housing 55 at the end of the duct 40 and provided with a bore 56. A tubular connector 57, secured to the outer end of the pipe 42, terminates in a parti-spherical head 59 located within the bore 56 and which universally engages the cup-shaped seat 60 of a washer 61 rotatably and slidably mounted in the bore 56. A nut 63 threaded on the housing 55 has an inturned flange 64 against which the washer 61 seats, and a coiled spring 65, engaged at one end in a recess 66 in the head 59, is compressed between the connector 57 and the bottom of the bore 56 to maintain the universal seated rotatable relation of the head 59 in the washer 61, so that the retort may be rotatably driven without transmitting its movement to the duct 40.

A cup-shaped closure member 70 removably fits within the retort end 23 and has an inner dome-shaped wall 71 which forms a closure for each of the carburizing chambers 15. This wall 71, which closely overlies the core end 22 to separate the loading ends of the chambers 15, has an annular bevelled face 72 removably seated against a similar face 73 in the retort wall at the end of the carburizing chambers. An end flange 74 on the member 70 is slotted at 75 to respectively receive the clamping screws 76 pivotally secured to the flange 37, and the thumb nuts 77 on the screws 76 engage the flange 74 and removably clamp the member 70 in seated position. The effluent pipes 78 extend through the end wall 71 and respectively communicate with each of the carburizing chambers 15 so that the spent carburizing gases may freely exhaust from the work. The closure member 70 and the retort end 24 between the cap 44 and the head 34 are each filled with a suitable heat insulating material 79 such as asbestos or a refractory material. The furnace 10 is provided with the intermediate heating chamber 80 surrounding the work holding portion 14, and, in the present instance, the heating medium is shown in the form of a series of electrically energized grids 81 supported in spaced relation to the inner furnace wall. However, it will be appreciated that any suitable form of heating may be employed. The heating chamber 80 has a refractory lining 82 surrounded by a suitable heat insulating material 83, such as asbestos or the like, held in position by an outer casing 85.

I claim:

1. In a device of the character indicated, a retort provided with a plurality of work-holding

chambers, a transverse wall closing said chambers at one end and having ports respectively extending therethrough into said chambers, a second wall engaging the retort in spaced relation to said first wall and providing a gas expansion chamber between said walls, and a duct communicating with said expansion chamber through said second wall; substantially as described.

2. In a device of the character indicated, a retort provided with a plurality of adjacent work holding chambers, a transverse wall closing one end of said chambers and having ports respectively communicating with said chambers, a peripherally disposed seat in the retort adjacent said wall, a dome-shaped head engaging said seat and spaced from said wall to provide a gas expansion chamber at one end of said ports, and a duct communicating with said expansion chamber through said head; substantially as described.

3. In a device of the character indicated, a retort having an intermediate work receiving portion provided with a plurality of adjacent sector-shaped work-holding chambers, a transverse wall closing one end of said chambers and having ports respectively extending therethrough into said chambers, an annular seat at the other end of said chambers, a second wall in spaced relation to said other wall and providing a gas expansion chamber between said walls communicating with said ports, a duct communicating with said expansion chamber through said second wall, a closure member removably engageable with said seat for closing the other end of the work-holding chambers, and effluent ducts respectively communicating with the work holding chambers through said closure member; substantially as described.

4. In a carburizing furnace, a rotatable tubular retort having an intermediate reduced work receiving portion, a transverse wall closing one end of said portion, the other end of said portion terminating in an annular seat within the retort, a hollow core opening through and longitudinally extending from said transverse wall through said portion, the other end of said core being closed, longitudinally disposed walls connected to said core and to said transverse wall and dividing the intermediate work receiving portion into sector-shaped work holding chambers, and a closure member closely overlying the closed end of the core and removably mounted in the retort against said seat to close said chambers.

DANIEL V. SCULLEN.
